UNITED STATES PATENT OFFICE.

SAMUEL C. HOEY, OF WILKINSBURG, PENNSYLVANIA, ASSIGNOR TO WESTINGHOUSE ELECTRIC & MANUFACTURING COMPANY, A CORPORATION OF PENNSYLVANIA.

LAMP-FIXTURE.

1,374,569.

Specification of Letters Patent. Patented Apr. 12, 1921.

Application filed November 19, 1917. Serial No. 202,698.

To all whom it may concern:

Be it known that I, SAMUEL C. HOEY, a citizen of the United States, and a resident of Wilkinsburg, in the county of Allegheny 5 and State of Pennsylvania, have invented a new and useful Improvement in Lamp-Fixtures, of which the following is a specification.

My invention relates to lamp fixtures and 10 particularly to means for attaching the globes thereof to the bodies of the same.

The object of my invention is to provide a simple and efficient means for securing globes having neck portions of different 15 widths to a lamp and for insuring an air-tight joint therebetween.

In lamp globes, of the type having a body portion of bowl shape and a cylindrical neck portion adjacent to the opening therein, it 20 is usual to provide a groove in the neck portion for the reception of a bail member. The bail member is, in turn, usually adapted to coöperate with stationary hook members on the lamp body to cause the neck portion of 25 the globe to engage its seat. It is thus obvious that, if the globe seat, hook members and bail member have a fixed permanent inter-relation, the neck portion of the globe will necessarily have to be of a predetermined width to provide an air-tight globe 30 closure.

In manufacturing globes of this type in large numbers, by reason of the nature of the facilities, it has been found a great step 35 in cheapening the cost of production to be permitted to ignore, within reasonable limits, the widths of the neck portions of the same.

In practising my invention, I provide, on 40 the underside of an incandescent lamp hood, a resiliently mounted relatively movable globe seat that telescopically engages a flange on the hood and, in conjunction with depending hooks on the hood and a bail 45 member, provide means for readily mounting and insuring an air-tight seat for a globe of the ordinary bowl type, regardless of the width of the neck portion of the same.

Figure 1 of the accompanying drawings is 50 a side view, partially in section, of a lamp embodying my invention, and Fig. 2 is an enlarged fragmentary view of a portion of the device shown in Fig. 1.

A main supporting housing or hood 1 55 comprises a petticoat member 2, an inter-

mediate body member 3, in which a lamp 4 may be positioned, and a cap member 5 having an eye 6 for attachment to the usual cross arm (not shown). An annular flange 8 depends from the underside of a sloping 60 roof portion 7 of the body member 3 and has recessed lugs 10 at points about its inner periphery that are internally screw-threaded for the reception of screws 11 having heads 12. A globe seat, comprising a 65 relatively thin ring member 13 having recesses at points about its periphery to loosely embrace the screws 11, rests upon the screw heads 12 and is yieldingly held in position by springs 14 that surround a portion 70 of the screws 11 and extend between the lugs 10 and the ring member 13. A cylindrical member 15, disposed co-axially with, and on, the ring member 13 at the outer periphery thereof, telescopically surrounds the 75 flange 8 and is adapted for slidable engagement therewith. Supporting hooks or members 16 depend from the inner side of the portion 7 of the member 3 and are adapted to coact, in a usual and well known manner, 80 with a bail member 17 that is disposed in a groove 18 of a globe 19 to support the same in position and to maintain the neck portion 20 of the globe in air-tight engagement with the ring or globe seat 13.

The globe seat 13 will be positioned, when the globe is mounted, in accordance with the axial width of the neck portion of the latter, and provision is thus made for the ready mounting of similar globes having 90 neck portions of different widths.

While I have shown and described a particular form of my invention, many changes may be made therein without departing from the spirit and scope of the same as 95 set forth in the appended claims.

I claim as my invention:

1. In a lamp, the combination with a lamp-supporting structure positioned at one side only of the globe, of a resiliently mounted globe seat on the supporting structure, 100 said seat comprising a ring, against which a globe is adapted to be held in abutting engagement, and means for compensating differences in the axial lengths of similar globes 105 therefor in maintaining the same in said abutting engagement.

2. A lamp structure comprising a lamp-supporting housing having a depending flange and depending lugs, and a member 110

providing a relatively movable air-tight globe seat resiliently attached to the lugs and embracing the flange at all times.

3. A lamp structure comprising a lamp-
5 supporting housing having a depending flange and depending lugs, a member pro-
viding a relatively movable air-tight globe seat resiliently attached to the lugs and embrac-
10 ing the flange, and means for re-
siliently securing a globe in contact with
the seat disposed on the housing.

4. A lamp structure comprising a lamp-
supporting housing having a depending flange and depending lugs, and a member
15 providing a relatively movable air-tight globe seat resiliently attached to the lugs and telescopically engaging the flange at
all times.

5. In a lamp structure, the combination
20 with a hood, stationary members depending
therefrom for supporting a globe having a
neck portion adjacent its open end, and a
bail member for supporting the globe dis-
posed on one side of the neck portion and
25 having a constant operative relation to the
said supporting members, of means com-
prising a globe seat movably disposed on
the hood for positioning the bail member,
regardless of variations in the width of the
30 said neck portion.

6. A lamp structure comprising a hood
having an inner cylindrical flange and re-
cessed depending lugs, screws disposed in
the lugs and having heads spaced there-
35 from, a circular globe-seat member resting
on the said heads, springs embracing the
screws between the lugs and the globe-seat
member, a cylindrical member for telescopi-
cally engaging the said flange mounted on
40 the globe-seat member, depending bail sup-
porting members on the hood, and a bail
member for disposition on a globe of the
usual bowl type on one side of the neck
portion thereof, the whole structure pro-
45 viding means for adjusting globes having
neck portions of different widths to the hood
and an air-tight joint therebetween.

7. The combination with a lamp struc-

ture having a support, an attaching member
having fixed operative relation to the sup-
port, a globe suspended from the attaching
member and having a rim portion disposed
between the support and the attaching mem-
ber, of a seat for the rim yieldingly disposed
between the support and the globe and mov-
able to accommodate variations in the di-
mensions of the portion of the globe between
the support and the said attaching member.

8. The combination with a lamp struc-
ture having a support, a globe having an open
60 end, and an attaching member for the
globe having a fixed operative relation to
the support for suspending the globe beneath
the hood, of an adjustable seat disposed
65 between the support and the attaching mem-
ber for engaging the open end of the globe
regardless of its relative position with re-
spect to the support.

9. In a lamp structure, the combination
with a closed hood, a globe having an open
end, and an attaching member for the globe
having a fixed operative relation to the hood
for suspending the globe beneath the hood,
of an adjustable sealing seat disposed be-
75 tween the hood and the attaching member
for engaging the open end of the globe
and substantially sealing the space between
the hood and the globe regardless of varia-
tions in the dimensions of the portion of
80 the globe between the hood and the point of
suspension of the globe.

10. In a lamp structure, the combination
with a hood, a bail member for supporting
a globe having a neck portion adjacent to
its open end, the said bail member being
85 disposed on one side of the neck portion
and having a constant operative relation to
the said supporting members, of a globe
seat movably disposed on the hood permit-
ting positioning of the bail member, regard-
less of variations in the width of the said
90 neck portion.

In testimony whereof I have hereunto
subscribed my name this 31st day of Oct.,
1917.

SAMUEL C. HOEY.
